DESIGN FOR A DESK

Bayard E. Richardson and Richard W. Willey,
Grand Rapids, Mich.

Application April 22, 1935, Serial No. 56,508

Term of patent 7 years

To all whom it may concern:

Be it known that we, Bayard E. Richardson and Richard W. Willey, citizens of the United States, residing at the city of Grand Rapids, in the county of Kent and State of Michigan, have invented a new, original, and ornamental Design for a Desk, of which the following is a specification, reference being had to the accompanying drawing, forming a part thereof.

The figure is a rear perspective view of the desk, showing our new design, the front of the desk being conventional.

The dominant feature of the design resides in the appearance of the rear of the desk.

We claim:

The ornamental design for a desk, as shown and described.

BAYARD E. RICHARDSON.
RICHARD W. WILLEY.
